UNITED STATES PATENT OFFICE

2,207,022

METAL VISE FOR TACK BUTTONS

Frederick H. Peterson, Watertown, Conn., assignor to The Patent Button Company, Waterbury, Conn., a corporation of Connecticut

Application August 11, 1938, Serial No. 224,387

10 Claims. (Cl. 24—94)

My invention relates to new and useful improvements in vises that are to be incorporated in tack buttons.

As is well known to those skilled in the art, 5 tack buttons may be made from a molded composition in which there is located a vise, or vise and anvil, so that when the tack is driven up into the button for attaching purposes, the vise will guide the tack within the button and deform the prong to thus securely attach the button to its cloth.

Or, in the same manner, when the tack button is formed with a thin metal shell and cap, there is provided a vise and anvil to likewise deform 15 the prong of the tack and hold the button head in place.

In both instances, the vise or the vise and anvil also prevent the prong of the tack from piercing or deforming the face of the button.

One of the principal objects, therefore, of the 20 present invention is to provide a vise about which may be molded the composition or plastic button, the vise being so constructed that it will not only assist in guiding the tack prong within the vise but will provide an ample size chamber for the deformed end of the tack and prevent the point from piercing the face of the molded button. Again, if the vise is used with a metal shell tack button, the vise will prevent the tack from 25 piercing and disfiguring the embossed cap and securely hold the deformed tack prong to thus attach the button to its cloth.

Still another object of the invention is to provide a vise that may be quickly and cheaply 30 manufactured and quickly assembled in a button structure.

Still another object of the invention is to provide a vise that is preferably made in two parts, that is, the body portion and a cap, the cap 35 being rimmed over the body portion to complete the structure.

Still another object of the invention is to provide a vise that has its upper portion depressed 40 to form a chamber to receive the deformed end of a tack prong and wherein the substantially integral cap may be eliminated and a separate anvil or blank positioned over the vise, if so desired. Still, in other instances, it may be possible to just utilize the vise and do away with 45 both the cap and the anvil.

Still another object of the invention is to provide a vise wherein the cap, when the cap form is used, in reality performs a double function, 50 that is, it functions as the top wall of the cham-

ber to complete the same and also acts as an anvil to deform the tack point.

Still another object of the invention is to provide a vise preferably made of two pieces of metal, wherein the cap may be easily fitted and rimmed about the body portion of the vise, and after once being rimmed cannot be removed therefrom, unless destroyed, as the greater the upward force of the tack the tighter the rim of the cap will pull about the rim of the body portion. 10

Still another object of the invention is to provide a new and novel form of vise that will guide, receive, and deform the end of the tack during the attaching operation and, at the same time, provide an ample chamber for the deformed tack prong, so that there is no likelihood or chance of the cracking of the plastic button during the attaching operation. 15

With these and other objects in view, the invention consists in certain new and novel features and combination of parts, as will be herein-after more fully explained and pointed out in the claims. 20

Referring now to the drawing showing a preferred and a modified form. 25

Fig. 1 is a greatly enlarged view of a partly formed blank from which the body of the vise is made;

Fig. 1^a is a similar view but showing the blank 30 as now being headed and the upper chamber before the same is pierced;

Fig. 2 is a sectional view of the blank as pressed into final shape and the upper chamber being pierced; 35

Fig. 3 is a top plan view of the vise before the cap is attached;

Fig. 4 is a sectional view of the cap ready to be rimmed on the body of the vise;

Fig. 5 is a bottom plan view of the vise; 40

Fig. 6 is a side elevation of the completed vise;

Fig. 7 is a sectional view of the completed vise incorporated in a molded or plastic button;

Fig. 8 is a bottom plan view of the button; 45

Fig. 9 is a view similar to Fig. 7, but showing the button attached to its material; and

Fig. 10 shows a slightly modified form, that is, the vise used in conjunction with a separate anvil. 50

At the outset, it might be mentioned that I have only illustrated the present vise as being incorporated in a molded button, but it may, of course, equally as well be used in a metal shell button.

It is also to be remembered that these vises 55

are relatively small, generally less than one-quarter inch in height and slightly over one-quarter inch in diameter across the cap, but for purposes of clearness of illustration, I have 5 shown the vise and the button on a greatly enlarged scale.

Referring now to the several views, I have shown in Fig. 1 the partly formed vise 1, which has been pressed from a small rectangular piece 10 of copper stock (not shown), copper being preferably used due to its ductility and to the further fact that it is rust-proof and will not be affected when used in a composition button.

In Fig. 1a, I have shown the further step in 15 the formation of the vise, the top surface having been partly depressed and the flaring rim being partly formed.

Referring now to Fig. 2, it will be seen that the small vise is circular in cross section and 20 comprises what I term the lower portion 2, which is bent upwardly and inwardly, as at 3, to form the slightly flaring entrance 4 and the restricted throat 5.

It will be noticed that the outer periphery is 25 rolled or depressed slightly, as at 6, and the wall then flares upwardly and outwardly, as at 7. By annularly depressing the wall in this manner, it permits the plastic of the button head to flow about the depressed portion and thus more tightly bind the vise against movement within the button head.

The top portion of the metal vise is bent downwardly and inwardly on itself, as may be seen at 8, to form the side walls of the chamber 9 for 35 the reception of the deformed tack prong, as will be shortly mentioned.

The metal that is pushed downwardly, as at 8, terminates at 10 just slightly above the upper edge of the metal, forming the restricted throat 40 5 heretofore mentioned.

In the formation of the vise, after the metal is forced downwardly at 18, it is pierced, so that the opening 11 is in direct registry with the opening of the restricted throat 5.

Now to form the dome of the chamber 9, in 45 the preferred form, there is provided the cap 12, as may be seen in Fig. 4, which is loosely fitted over the flared rim 7 of the vise and then rimmed or rolled, so that the downwardly extending flange 13 of the cap will snugly fit about the outer periphery of the flared portion 7, as 50 may be clearly seen in Figs. 7 and 9.

When this cap is fitted in place, it will be seen 55 that the chamber 9 is completed and will accommodate the deformed end 14 of the prong 15 of the tack 16.

The cap can be of metal of any desired weight or thickness, so that when the tack 14 in the attaching operation is driven up into the vise, it 60 will be turned and deformed, as may be seen in Fig. 9, without any possibility of going through the cap.

In Figs. 7 and 9, I have shown the vise molded 65 within the plastic button 17. This button has the integral hub 18, the flared head portion 19, while a relatively large entrance 20 may be seen, so that if the tack tends to bend in its attaching operation, it will not contact with the side walls, which might tend to crack or break the button.

In Fig. 9, I have shown the tack with its prong 70 15 having pierced the cloth 21 and deformed within the chamber 9, thus holding the button tightly in its final position.

It will also be seen from Fig. 9 that the side 75 walls of the chamber 9 are such that when the

end of the prong 14 is deformed against the cap, it will be jammed against the downwardly sloping walls 8, which may give slightly without transferring the strain to the button.

It will be noticed from Figs. 7 and 9 that the top wall 22 of the button above the vise is relatively thin, but I have found in the molding of numerous buttons that there is no likelihood of this plastic wall cracking, due to the rigidity of the vise and to the fact that the end of the prong may be easily accommodated within the chamber 9.

The tack will be guided while entering the vise through the restricted throat 5 and also will be guided by the lower end of the walls 8 that form the chamber 9, so that there is little likelihood of the tack being driven anywhere except into its receiving chamber 9.

In the modified form as shown in Fig. 10, it will be seen that the vise proper V is in every respect similar to the vise shown in the preferred form, with the exception that in this instance, the usual cap is eliminated. However, in the button 17' just above the vise V, there is provided the separate blank or anvil 23 to complete the chamber, so that when a tack is driven up into the vise, its prong will impinge against the said anvil 23, as will be readily understood, and be deformed within the chamber of the vise.

This vise without the integral cap is also readily adaptable for metal shell buttons, as the vise rests within the hub while the anvil placed directly over the vise will be held in place by the button cap (not shown).

From the foregoing, it will be seen that I have provided a vise preferably formed of two parts, which, when assembled, constitute substantially an integral structure.

Due to the internal structure of the vise, the tack, during the attaching operation, will be properly guided up into its chamber, where it will strike against the cap and be readily deformed. Also, due to the size of the chamber and its somewhat resilient side wall, the deformed prong will be readily accommodated while the internal walls of the chamber may give slightly without transferring the strain to the outer walls of the vise and consequently to the button.

Finally, in the preferred form, by constructing the vise as shown, an economy may be effected in that the body may be of lighter gauge material than the cap. It will also be understood that it may be possible to use the vise without either a cap or an anvil if the vise were to be used in, say, a solid metal button wherein the top wall of the button would be capable of turning the tack and deforming it within the vise chamber.

Having thus described my invention, what I claim as new and desire to secure by Letters Patent is:

1. A metal vise for tack buttons comprising a body portion, said body portion annularly depressed, the upper end of the vise extending back within itself to form the side walls of a slightly resilient flaring chamber, the bottom of the vise being perforate and extending upwardly and inwardly to form a slightly restricted throat for the guidance of the prong of the tack fastener, the said chamber being open at its bottom and the said opening being in registry with the said throat whereby on the attaching operation, the tack fastener is guided through the throat into the chamber to be deformed and accommodated within said chamber.

2. A metal vise for tack buttons comprising a

body portion flared at its upper end, the bottom of the vise provided with a restricted opening for the guidance of the tack fastener, the side walls of the vise extending downwardly and back on themselves thus forming a chamber in the upper portion of the body of the vise, the confining walls of the chamber being slightly resilient and the said chamber adapted to accommodate the deformed end of a tack fastener.

3. A metal vise for tack buttons comprising a body portion, the bottom of the vise provided with a restricted opening for the guidance of a tack fastener, an integral chamber formed in the upper portion of the body of the vise by extending the walls of the vise downwardly and inwardly, the resultant confining walls of the chamber being slightly resilient, and means secured to the upper end of the vise for closing the upper portion of said chamber and for deforming the end of a tack fastener.

4. A metal vise for tack buttons comprising a body portion, the bottom of the vise provided with an opening for the guidance of a tack fastener, the side walls of the vise extending downwardly and inwardly of the vise to thus form an open chamber in the upper portion of the body of the vise, the confining walls of the chamber being slightly resilient, and means for closing the said open end of the chamber, said means crimped about the upper end of the vise adapted to deform the end of a tack fastener within said chamber.

5. A metal vise for tack buttons comprising a body portion, a cap tightly fitted over the upper end of the body portion, the bottom of the vise provided with a restricted opening for the guidance of a tack fastener, the walls of the vise extending downwardly and inwardly to form a substantially conical chamber in the upper portion of the body of the vise, the confining walls of the chamber being slightly resilient, the cap of the vise adapted to deform the end of the tack fastener and the chamber adapted to accommodate the same.

6. A metal vise for tack buttons comprising a body portion, the said body portion annularly depressed about midway its height, the upper end of the vise extending back within itself to form a slightly resilient chamber, a cap fitted over the upper end of the vise, the bottom of the vise having a restricted opening for the reception and guidance of the prong of the tack fastener, and the cap adapted to deform the prong of the fastener within said chamber to thereby hold the button in a securely attached position.

7. A metal vise for tack buttons comprising a body portion, said body portion annularly depressed, the upper end of the vise extending back within itself to form the side walls of a slightly resilient flaring chamber, a dome-shaped cap fitted over the upper end of the vise to complete the chamber, the bottom of the vise being perforate and having its end rolled upwardly and inwardly to form a flaring opening and a slightly restricted neck for the guidance of the prong of the tack fastener, the chamber being open at its bottom and in registry with the restricted neck whereby on the attaching operation the tack fastener is guided through the neck up into the chamber and deformed against the cap and accommodated within said chamber.

8. A metal vise for tack buttons formed of a body portion and a cap, the walls of the upper end of the vise extending downwardly and inwardly within the vise to form a slightly resilient internal flaring chamber, the cap rimmed about the upper edge of the vise, the bottom of the vise being perforate and having the walls about the perforation extending upwardly and inwardly within the vise, the lower end of the internal chamber and the upper end of the walls about the perforation being in registry to thus form means for guiding the tack prong within the chamber during the attaching operation and the cap acting as an anvil to deform the tack within the said internal chamber.

9. A metal vise for tack buttons comprising a body portion formed of tubular stock having its upper end bent downwardly and inwardly within the body to form a flaring chamber, the bottom of the chamber being perforate, a cap rimmed about the upper end of the vise to complete the walls of the chamber, the bottom of the vise being perforate and having a flaring opening and a slightly restricted neck, the two openings being in registry and in close proximity, the cap adapted to deform the prong of the tack fastener within the resilient walls of said chamber.

10. A vise for tack buttons formed of two parts, said vise including a body portion with a flaring upper end and a cap tightly rimmed about the same, integral re-entrant internal walls forming a chamber within the vise, the bottom of the vise being perforate and the walls about the perforation rolled inwardly and upwardly, the said vise adapted to deform and accommodate the prong of a tack fastener.

FREDERICK H. PETERSON. 55
